United States Patent

Des. 236,260

Patented Aug. 12, 1975

236,260

VEHICLE ATTACHED PUSH BUMPER

John H. Allmand, 21253 Woodhill Drive,
Farmington Township, Mich. 48024

Filed Sept. 21, 1973, Ser. No. 399,414

Term of patent 14 years

Int. Cl. D12—16

U.S. Cl. D12—169

FIG. 1

FIG. 2

FIG. 4

FIG. 3

FIG. 1 is a front perspective view of a vehicle attached push bumper, showing my new design;

FIG. 2 is a top plan view thereof;

FIG. 3 is a side elevational view thereof; and

FIG. 4 is a rear elevational view thereof.

I claim:

The ornamental design for a vehicle attached push bumper, as shown.
